UNITED STATES PATENT OFFICE.

SAMUEL M. LANGSTON, OF CAMDEN, NEW JERSEY.

ADJUSTING AND DRIVING MECHANISM FOR SHAFTS.

1,086,722.

Specification of Letters Patent. Patented Feb. 10, 1914.

Application filed February 5, 1913. Serial No. 746,289.

To all whom it may concern:

Be it known that I, SAMUEL M. LANGSTON, a citizen of the United States, and resident of Camden, in the county of Camden and State of New Jersey, have invented certain new and useful Improvements in Adjusting and Driving Mechanism for Shafts, of which the following is a specification.

In printing presses as well as in certain other machines it is often necessary to bodily adjust a driven roller or shaft toward or from another and to maintain absolute parallelism of movement. By means of my invention I am able to secure the simultaneous and equal adjustment of the opposite ends of a roller or shaft and to drive the bodily adjustable roller or shaft with the same speed and accuracy in one position as in another and with the driving gears in proper mesh at all times.

My invention is particularly applicable to rotary printing presses in which spaced type and impression cylinders are employed one of which is adjustable toward and from the other to accommodate the machine to stock of various different thicknesses. In such machines it is essential that the distance between the rollers be the same at one end as at the other and it is highly important that the drive of the movable cylinder operate with equal efficiency when the cylinder is in all of its adjusted positions.

My invention is also applicable to the rollers of embossing presses or lithographing machines or it might be embodied in machines designed for other purposes.

Reference is to be had to the accompanying drawings in which similar characters of reference indicate corresponding parts throughout the several views.

Figure 1 is an end view of a part of a machine constructed in accordance with my invention, a portion thereof being broken away; Fig. 2 is a vertical longitudinal section through a portion of the machine showing the rollers spaced at a considerable distance apart; Fig. 3 is a transverse section taken substantially on the line 3-3 of Fig. 1; Fig. 4 is a sectional detail taken substantially on the line 4-4 of Fig. 1, and Figs. 5 and 6 are horizontal sections through the upper and lower pairs of cylinders.

My invention is applicable for use in connection with any rotary printing press or other analogous machine in which there are two shafts or rollers which are relatively

adjustable toward and from each other and in which it is desired to drive the adjustable cylinder.

I have illustrated my invention in connection with a printing press having a pair of upper type cylinders 10, 10 and a pair of lower impression cylinders 11, 11. The impression cylinders are mounted to rotate about fixed axes and have their upper surfaces substantially flush with or closely adjacent to the upper surface of the main table or platform 12 of the machine. The lower cylinders are carried by shafts 13 mounted in suitable bearings in the main frame 14 of the machine and are provided with suitable gear wheels 15 intermeshing with an intermediate idler 16 which may be mounted upon a stub shaft and which insures the simultaneous rotation of both lower cylinders at the same speed. Power may be applied to the shaft of either lower roller to positively drive the same, such driving means forming no portion of my invention and not being illustrated.

The upper or type cylinders 10 are mounted on shafts 17 which latter are journaled in bearings carried by vertically movable standards or slides 18. These slides may be guided in any suitable manner in the main frame so that no movement other than a longitudinal one is possible. For positively insuring the simultaneous vertical movement of both ends of an upper cylinder I provide a transverse shaft 19 adjacent the lower portion of the machine and upon this shaft mount two pinions 20 intermeshing with rack teeth 21 on the sides of the vertically movable supporting member for the upper roller. As both pinions are rigid on the shaft it is evident that a rotation of one end of the shaft will insure a corresponding rotation of the opposite end and as the weight of the cylinder is borne largely by the engagement of the rack teeth with the pinions, there will be no lost motion in the engagement between the latter and a rotation of one end of the shaft will insure a simultaneous and equal vertical movement of both ends of the corresponding upper or type cylinder.

For rotating the shaft and securing the desired delicacy of adjustment I provide the shaft adjacent one end with a lever 22 rigid thereon and abutting against an adjustable set screw 23. The set screw may have a hand wheel to facilitate the rotation thereof.

By turning the said screw in one direction the lever will be caused to swing and the upper rollers will be raised to the desired extent. A rotation of the set screw in the opposite direction will permit the rollers to be lowered by their own weight.

In Figs. 3 and 4 I have shown both ends of the shaft 19 provided with arms 22 and regulating set screws, but it is only necessary that such be provided on one end and it is immaterial which end is employed. By having the arms on both ends the pressman may adjust the roller from which ever side of the machine is most convenient. It will be noted that in case a piece of stock of extra thickness reaches the rollers the latter are free to move upwardly and permit the passage of the stock without liability of breaking or injuring the machine as the upper per roller is held down solely by its own weight. The extent of the adjustment may be limited if desired but ordinarily it is not necessary. I have shown the vertically movable standards or slides 18 provided with slots 24 through which the shafts 13 of the lower rollers extend and these slots should be of a length at least equal to the maximum adjustment which would ever be required in the machine.

In order to insure the positive and proper driving of the upper cylinders when in any desired adjusted position I provide the shafts 13 and 17 with gears 25 and 26 of the same size but of such diameter as not to interfere. I pivot upon each lower shaft 13 an arm or link 27 and pivot upon each upper shaft 17 an arm or link 28. These links are each of a length somewhat greater than the radius of the gears 25 and 26 and are pivoted together by a pintle 29 which also carries a pinion 30 meshing with one of the gears 25 or 26. As illustrated the upper arm 28 is slightly shorter than the lower arm 27 and the pinion 30 meshes with the upper gear 26 but not with the lower gear 25. Journaled on a suitable stub shaft on the lower arm 27 is a pinion 31 meshing with the pinion 30 and with the lower gear 25. Thus it will be noted that the rotation of the lower gear 25 causes an equal and opposite rotation of the upper gear 26 and the opposed surfaces of the upper and lower cylinders will travel in the same direction and at the same speed. As the upper cylinder is raised or lowered the arms or links 27 and 28 will swing about the two shafts as centers, but the pinions will at all times remain in perfect mesh and proper driving of the upper cylinder will be insured.

Having thus described my invention, what I claim as new and desire to protect by Letters-Patent is:—

1. In a machine of the type specified, a frame, an upper and a lower roller shaft mounted in said frame, pivotally connected

links connecting said shafts, means for varying the relative positions of said shafts to limit the minimum distance between them and at the same time varying the angle of said links, and means adapted to rotate one of said shafts in unison with the other, said means including elements carried by said links.

2. In a machine of the type specified, a frame, an upper and a lower roller shaft mounted in said frame, pivotally connected links connecting said upper and lower shafts, gears connected to said shafts, intermediate driving gears mounted between said first-named gears and mounted on said links whereby said shafts may rotate in unison, and means for changing the relative positions of said shafts and at the same time varying the angle of said links in respect to each other.

3. In a machine of the type specified, a frame, an upper and a lower roller shaft mounted in said frame, links connecting said shafts and adapted to vary their relative positions, rack bars connected to one of said shafts, a shaft having gears meshing with said rack bars means for rotating said last mentioned shaft to vary the position of one of said first mentioned shafts and to vary the angle of said links and means for transmitting motion from one of said shafts to the other irrespective of their relative positions.

4. In a machine of the type specified, a frame, an upper and a lower roller shaft mounted in said frame, links connecting said shafts and adapted to change their relative positions, reciprocating rack bars attached to one of said shafts, a shaft having gears meshing with said rack bars, means for rotating said last mentioned shaft in one direction and varying the angle of said links, gears operatively attached to said first-mentioned shafts, and idler gears mounted on said links between said second-mentioned gears.

5. In a machine of the type specified, a frame, an upper and a lower roller shaft mounted in said frame, links connecting said shafts, longitudinally movable bars for varying the relative positions of said shafts and varying the angle of said links, and means including elements on said links for rotating one of said shafts in unison with the other.

6. In a machine of the type specified, a frame, a lower roller having a shaft journaled in said frame, an upper vertically movable roller having a shaft, links connecting said shafts, means for raising the upper roller and limiting its downward movement, said upper roller being free to move upwardly against gravity upon the passage of excessively thick material between said rollers and means adapted to ro-

tate one of said rollers in unison with the other said means including elements carried by said links.

7. In a machine of the type specified, a frame, a roller shaft mounted therein, a drive shaft, links connecting said shafts, non-intermeshing gears on said shafts, manually operable means for separating said roller shaft and said drive shaft and limiting the minimum distance between them, and means on said links, serving to uniformly transmit power to said roller shaft from said drive shaft irrespective of the adjusted position of the former.
8. In a machine of the type specified, a frame, a roller having a shaft mounted therein, a drive shaft, links connecting said shafts, non-intermeshing gears on said shafts and manually operated means for positively raising said roller shaft and normally preventing the return movement thereof, said means permitting the continued upward movement of said roller shaft against gravity by the pressure of material passing beneath said roller, and means on said links, serving to uniformly transmit power to said roller shaft from said drive shaft irrespective of the adjusted position of the former.
9. In a machine of the type specified, a frame, a lower roller having a shaft journaled in said frame, oppositely disposed vertically extending slides mounted on said

frame and each having an opening intermediate of its ends and larger than said shaft through which the latter extends, an upper roller having its shaft journaled in said slides at the upper ends of the latter, means at the lower ends of said slides below said lower roller for simultaneously moving said slides endwise, non-intermeshing gears on said shafts, links connecting said shafts and means on said links for transmitting motion from said first mentioned shaft to said second mentioned shaft irrespective of the position of said slides.

10. In a machine of the type specified, a frame, a lower roller having a shaft journaled in said frame, oppositely disposed slides mounted on said frame, an upper roller having its shaft journaled in said slides at the upper ends of the latter, means at the lower end of said slides and below said lower roller for elevating said slides and said upper roller, pivotally connected links movable with said slides and gears carried by said links for transmitting motion from said first mentioned shaft to said second mentioned shaft.

Signed at New York city, in the county of New York and State of New York, this 4th day of February, A. D. 1913.
